H. H. BROWN.

PANEL BOX.

APPLICATION FILED MAY 31, 1919.

1,355,887.

Patented Oct. 19, 1920.

UNITED STATES PATENT OFFICE.

HECTOR H. BROWN, OF BALTIMORE, MARYLAND, ASSIGNOR TO RIGGS, DISTLER & STRINGER, INCORPORATED, A CORPORATION OF MARYLAND.

PANEL-BOX.

1,355,887.

Specification of Letters Patent. Patented Oct. 19, 1920.

Application filed May 31, 1919. Serial No. 300,948.

To all whom it may concern:

Be it known that I, HECTOR H. BROWN a citizen of the United States of America, residing in the city of Baltimore, State of Maryland, have invented certain new and useful Improvements in Panel-Boxes, of which the following is a specification.

This invention relates to an improved type of switch box, wall box or cabinet. Such boxes are ordinarily supplied to suit the requirements of each particular job and are then fitted with a commercial form of wood front furnished separately to conform as far as possible to the style of the surroundings. These wood fronts generally have a marginal area or zone which can be drilled for fastening to the box arranged as may suit the convenience of the maker. Difficulty is often experienced in attaching this to the box as registering holes must be drilled or punched in the box and front. This work is done at the place of installation with ordinary hand tools and is expensive and unsatisfactory on account of injury to the box, etc. Also, the boxes as now furnished often have no convenient points of attachment, *i. e.*, portions which can be drilled to receive the screws or bolts as necessarily spaced on account of the structure of the wood front.

Boxes of this type are intended to receive panels of insulating material on which the fuses, binding posts and switches are mounted. These panels of insulating material, as hard rubber, slate or the like, are brittle and difficult to work. They are therefore provided with screw-holes, screws or other fastening means at the factory. It is generally necessary to drill the boxes to conform to the plates or panels. As it becomes necessary to do this where the equipment is being installed, there is much loss of time and disfigurement of the structure.

To overcome this and other difficulties is an object of the present invention. To this end the cabinet or box is provided with fastening means arranged to conform to any spacing or combination of fastening means which may be supplied with the panel.

In the accompanying drawing I have illustrated a panel box or cabinet embodying the features of my invention. In the drawing—

Figure 1 is an elevation of the empty box with the front removed.

Fig. 2 is a section on the line 2, 2 of Fig. 1.

Fig. 3 is an elevation looking into the box with the front removed showing the arrangement of the panel and other equipment.

Fig. 4 is an elevation showing the front of the panel, box or cabinet, the door being in place and closed.

Referring to the drawing by numerals, the box 1 is of any suitable sheet material open on one of the large sides and having the edges of the walls flanged around the opening, the flanges being indicated by reference character 2. These flanges may be mitered at the corners at 3 or otherwise suitably arranged and fitted. The flanges 2 which preferably surround the front opening 4 on all sides are slotted at 5, the slots being extended in the direction of the length of the flanges. These slots 5 are intended to receive screws or other fastening means 6 on the wood fronts which are supplied commercially ready to apply. In a great many instances the fronts are so arranged that they may be bored for the screws anywhere on a particular margin. This margin is sufficient to make it convenient to conform to the slots 5, *i. e.*, to pass the fastening screws through these slots when otherwise it would be necessary to drill or punch the box.

The function of the box in the present instance is to hold the panel 7 carrying the equipment 8 which may be switches, terminals, fuses or the like. These panels come in various sizes and it is often desirable to change with a change of equipment. They are also drilled at points chosen by the manufacturer to provide fastening means which are ordinarily seated by drilling or punching the back of the box. This as already pointed out is inconvenient as it generally has to be done when the work is installed and without suitable equipment.

In the present instance the fastening of the panel is made easy by the provision of the support 10 which is a subject of the invention. This consists of parallel Z-bars or other conveniently arranged members 11. These as shown have one flange secured to the back of the box and the other flange slotted longitudinally at 12, the slots in the two members being parallel. To these parallel bars 11 are secured transverse plates or

slotted bars 14. The slots 15 therein are elongated and extend in the direction of the length of the plates and at right angles to the slots in the members 11. These transverse plates or bars 14 are preferably in the form of Z-bars as indicated in Fig. 2, the bottom portion 16 of the Z being cut off at the ends so that it fits between the Z-bars 11, the top portion 17 containing the slots 15 resting on the bars 11 and being apertured at 18 to receive screws or bolts 19 holding the bars 14 which screws pass through and are adjustable in the slots 12 of the Z-bars 11. Thus we have supports 14 for the panel with elongated slots 15 freely adjustable transversely to the direction of said slots 15 and for the entire extent of the box, so that whatever the arrangement of the fastening means or screws in the panel, they are received in the slots 15 and accommodated by some adjustment of the support.

The operation or rather the use of the invention will be easily understood from the description which in a general way is intended to disclose a cabinet or panel box adapted to receive any suitable commercial wooden or steel front of suitable size and any panel without the necessity for drilling or punching the box in order to install such portion of the equipment.

I have thus described specifically a single embodiment of my invention in order that its nature and operation may be understood to those skilled in the art; however, the specific terms herein are used descriptively rather than in their limiting sense, the scope of the invention being defined in the claims.

What I claim and desire to secure by Letters Patent is:

1. A panel box having a support for the panel consisting of substantially parallel flanged bars, each bar having one flange secured to the box and the other flange slotted in the direction of the length of the bar; slotted transverse members secured at their ends in said aforementioned slots, the slots in said members being transverse to the first-mentioned slots, and adapted to receive the fastening means for the panel.

2. A panel cabinet having parallel Z-bars each Z bar having one flange secured to the box, the other flange being provided with fastening means in elongated arrangement and transverse members adjustably secured to said Z-bars by said means, said transverse members having fastening means for the panel in arrangement elongated in the direction of their length.

3. A panel cabinet having parallel Z-bars each Z bar having one flange secured to the box, the other flange being provided with fastening means in elongated arrangement and transverse Z-bars adjustably secured to said Z-bars by said means, said transverse Z-bars having fastening means for the panel in arrangement elongated in the direction of their length.

Signed by me at Baltimore, Maryland, this 29 day of May, 1919.

HECTOR H. BROWN.
